CLAIM

The ornamental design for a bike rack, as shown and described.

DESCRIPTION

FIG. 1 is a front, right and top perspective view of a bike rack, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising a part of a rack. The broken lines in the drawings depict portions of the bike rack that form no part of the claimed design. In addition, the dot-dash broken lines in the drawings illustrate an enlarged portion of the design.
